AROMATIC NITROGEN COMPOUNDS

Adrien S. Du Bois, Jersey City, N. J., and Emery I. Valko, New York, N. Y., assignors to Onyx Oil & Chemical Company, Jersey City, N. J., a corporation of Delaware

No Drawing. Continuation of application Serial No. 564,548, November 21, 1944. This application December 28, 1946, Serial No. 719,139

9 Claims. (Cl. 260—290)

1

Our invention relates to novel organic compounds particularly valuable for use as surface active agents and as germicides. The compounds are characterized in that they contain at least two side groups in para relation on a benzene nucleus, one of these side groups being an alkyl group containing six to eighteen carbon atoms, the other being a group comprising an alkyl portion terminating in an ionizing, basic nitrogen atom.

This application is a continuation of our application, Serial Number 564,548, filed November 21, 1944, dealing with the production of alkoyl phenyl alkyl halides.

The preferred compounds of our present invention conform to the formulae

in which R is an alkyl radical containing six to eighteen carbon atoms, n is an integer greater than 1, X is a halogen atom, most suitably a bromine or chlorine atom, R₁, R₂ and R₃ are hydrogen or monovalent hydrocarbon radicals and in which the circle (Formula I) indicates that the nitrogen atom is part of a heterocyclic ring system. As exemplary of such compounds may be mentioned: hexyl phenethyl pyridinium bromide, dodecyl phenethyl pyridinium bromide, octyl phenethyl pyridinium bromide, lauryl phenylpropyl quinolinium chloride, undecyl phenylbutyl quinolinium chloride, hexadecyl phenylpropyl picolinium bromide, octadecyl phenethyl isoquinolinium bromide, heptyl phenethyl ammonium chloride, octadecyl phenylpropyl ammonium bromide, undecyl phenylbutyl trimethyl ammonium bromide, hexyl phenethyl dimethyl ammonium chloride, nonyl phenylpropyl benzyl ammonium bromide, the chlorides and bromides of N-hexa phenethyl morpholine, etc.

In addition to compounds meeting the type formula, supra, our invention embraces compounds in which the nitrogen atom forming part of one of the two necessary groups attached to the benzene nucleus has a valency of three.

Although other methods of preparation are possible, we usually prepare our preferred compounds by one of two methods:

2

(a) Reduction of compounds of the formulae

in which R, n, etc. have the same significance as in the preceding formulae.

(b) Reaction of compounds of the formula

in which R, n, etc. have the same significance with ammonia or with amines such as those indicated by the list of representative compounds above, e. g. pyridine, quinoline, isoquinoline, diethylamine, trimethylamine, benzylamine, morpholine, etc.

We have found that the reduction procedure, which results in the conversion of the carbonyl radical to a methylene radical with the result that the compound becomes more surface active, proceeds with particular advantage when nascent hydrogen produced by contacting metallic zinc, preferably in granulated form, with concentrated aqueous hydrochloric acid is employed as the reducing agent.

The carbonyl-containing compounds subjected to reduction are readily prepared in accordance with our copending application, Serial No. 719,140, filed December 28, 1946, by reacting the corresponding alkoyl phenylalkyl halide,

produced as by the acylation of the corresponding halogenated-alkyl phenyl compounds described therein in the presence of a Friedel-Crafts catalyst with an amine. In place of the amine, ammonia may be used, the choice as between ammonia and amines and as between amines being determined, of course, by the product desired upon the reduction.

The compounds of Formula V used in method (b), supra, are advantageously produced according to our copending application, Serial No. 719,138, filed December 28, 1946, by reduction of the corresponding alkoyl compounds, i. e. compounds meeting Formula VI.

Compounds within the scope of our invention, 60 but which do not meet the type formulae, first

given herein, are prepared when compounds of the formula

VII

in which R, R₁, R₂, and n have the same significance as heretofore are subjected to treatment, as with nascent hydrogen, preferably used in the presence of a solvent, ethylene glycol diethyl ether, for example, to convert the carbonyl radical to a methylene radical. Dodecyl phenethyl diethyl amine and hexyl phenethyl diethyl amine are exemplary of compounds we produce by this method.

The following examples are submitted by way of illustrating practices of our invention.

Example I

10 parts by weight of p-hexyl phenethyl bromide were mixed with 3 parts by weight of pyridine and the mixture kept at 150° C. for three hours. The mixture was extracted with petroleum ether in order to remove unreacted material and byproducts. The p-hexyl phenethyl pyridinium bromide thus obtained was soluble in water and when tested for its anti-bacterial properties in accordance with Circular No. 198 of the United States Department of Agriculture it killed *Eberthella typhosa* in 10 minutes, in a dilution of 1:4,500 at 20° C.

Example II

78 parts by weight of dodecyl phenethyl bromide were mixed with 20 parts by weight of pyridine and the mixture kept at 140° C. for three hours, whereafter it was extracted with petroleum ether. The product was soluble in water. Its killing dilution was 1:3,000 against *Eberthella typhosa* at 20° C. Titration for bromine demonstrated that the chemical formula was that of dodecyl phenethyl pyridinium bromide.

Example III

20 parts by weight of octyl phenethyl bromide were mixed with 5 parts by weight of pyridine and the mixture kept at 140° C. for one hour. After extraction with petroleum ether, the titration for bromine demonstrated that the product was octyl phenethyl pyridinium bromide. Its killing dilution was 1:1,600 against *Eberthella typhosa* at 20° C.

Example IV

6 parts by weight of lauroyl phenethyl diethylamine was treated for six hours with a mixture containing 40 parts by weight of ethylene-glycol diethyl ether, 150 parts concentrated aqueous HCl, and 30 parts by weight of zinc granules. Gaseous HCl was bubbled through the well-agitated reaction mixture for six hours. After this, the reaction mixture was mixed with aqueous caustic soda until it became alkaline and was extracted with ether. Evaporation of the ether yields dodecyl phenethyl diethyl amine.

Example V

4 parts by weight of caproyl phenethyl diethyl amine were mixed with 60 parts by weight of ethyl alcohol, 150 parts by weight of concentrated hydrochloric acid and 30 parts by weight of zinc granules. The reaction is carried out as in Example IV. The reaction product is distilled under 4 mm. Hg pressure at 154°-157° C. yielding hexyl phenethyl diethyl amine.

We claim:

1. p-Hexyl phenethyl pyridinium bromide.
2. p-Dodecyl phenethyl pyridinium bromide.
3. p-Octyl phenethyl pyridinium bromide
4. Organic chemical compounds conforming to the formula

10 in which R represents an alkyl group of 6 to 18 carbon atoms, n is an integer greater than 1, and A is a radical of the class consisting of the radicals of the hydro-halide salts of amines, the quaternary alkyl ammonium halide radicals and the pyridinium, quinolinium, isoquinolinium, morpholinium, and picolinium radicals, the radical A containing but one nitrogen atom and that being linked directly to the terminal carbon atom of the (CH₂)_n group.

15 20 5. Organic chemical compounds conforming to the formula

25 in which R represents an alkyl group containing from 6 to 18 carbon atoms, n represents an integer greater than 1, and R₁, R₂, and R₃ are selected from the group consisting of hydrogen and 30 monovalent hydrocarbon radicals, in which N is linked directly to the terminal carbon atom of the (CH₂)_n group, and in which X represents a halogen atom.

35 6. Organic chemical compounds conforming to the formula

40 45 in which R represents an alkyl group containing from 6 to 18 carbon atoms, n is an integer greater than 1 and A' is a quaternary ammonium radical of the class consisting of pyridinium, quinolinium, picolinium, isoquinolinium and the morpholinium radicals, the nitrogen of the A' radical being linked directly to the terminal carbon of the (CH₂)_n group and also to a halogen atom.

7. The organic chemical compounds of claim 4 in which A is the trimethyl ammonium chloride radical.

8. The organic chemical compounds of claim 4 in which A is the triethyl ammonium chloride radical.

9. A compound represented by the following formula:

55 where R is an alkyl radical containing at least 7 carbon atoms, n is an integer greater than one, N≡R₁ is a tertiary amine, X is an anion.
